UNITED STATES PATENT OFFICE.

EPPA H. RYON, OF WALTHAM, MASSACHUSETTS, ASSIGNOR TO CROMPTON & KNOWLES LOOM WORKS, A CORPORATION OF MASSACHUSETTS.

SPOOL-BEARING BRACKET FOR YARN-TUBE FRAMES.

Application filed June 30, 1922. Serial No. 571,853.

To all whom it may concern:

Be it known that I, EPPA H. RYON, a citizen of the United States, residing at Waltham, in the county of Middlesex and State 5 of Massachusetts, have invented a new and useful Spool-Bearing Bracket for Yarn-Tube Frames, of which the following is a specification.

This invention relates to yarn tube frames 10 as commonly used in large numbers in moquette looms. My invention is particularly directed to the provision of an improved bearing bracket for supporting the yarn spool on the tube frame and also for attaching 15 the assembled spool and tube frame to the pattern chain.

It is the general object of my invention to provide a form of bearing bracket which is simple in construction, economical in manufacture and which possesses important mechanical advantages which will be herein-after described and more particularly pointed out in the appended claims.

Two forms of my invention are shown in 25 the drawings, in which

Fig. 1 is an end view of one form of my improved construction;

Fig. 2 is a sectional side elevation taken along the line 2—2 in Fig. 1;

Fig. 3 is a transverse sectional elevation taken along the line 3—3 in Fig. 2;

Fig. 4 is a sectional plan view taken along the irregular line 4—4 in Fig. 2;

Fig. 5 is a plan view of the blank from 35 which this form of my improved bracket is made; and

Fig. 6 is a sectional side elevation of a modification.

Referring to the drawings, I have shown 40 a portion of a spool 10 and rectangular tube frame 11 to which the yarn tubes 12 are secured, these parts being of a usual form.

My improved spool bearing bracket is 45 preferably formed from a single piece of sheet metal, as shown in Fig. 5, and comprises a body having a bearing portion 15, side portions 16 and a bottom portion 17. The bearing portion 15 is formed by partially severing the same from the surrounding metal which is thereafter bent outward, as shown in Fig. 2, to form an attaching portion 18 adapted to project between the links 19 of the usual pattern chain on which the assembled yarn spools and tube frames 50 are transported. The bearing portion 15 is

preferably bent inward, as also shown in Fig. 2, and is provided with a hole to receive the journal stud or gudgeon 20 on which the spool 10 rotates.

The side and bottom portions 16 and 17 60 are bent at right angles to the body of the bracket and are adapted to extend into and fit closely within the end of the rectangular tube 11. One or more of these portions 16 and 17 may be threaded at 21 to receive 65 screws 22 by which the bracket is held from displacement in the tube. The parts 16 and 17 are preferably depressed around the threaded holes 21, thus affording more room for the countersunk heads of the screws 22, as 70 the walls of the tube 11 are formed of relatively thin metal.

A narrow slot 23 is formed in the body of the bracket to receive the lower end 24 of a hook 25 by which the tube frame and 75 spool are secured to the chain links 19. The hook itself is preferably struck up or otherwise thickened and is curved along its lower edge as shown in Fig. 1, this curved edge permitting easy swinging movement of the 80 brackets on the supporting chain.

The lower end 24 of the hook is preferably formed substantially as shown in section in Fig. 2, with a U-shaped bend 26 connecting the end 24 to the hook 25. The 85 portion 27 of the bracket body directly below the slot 23 is preferably slotted at the sides so that it may be bent outward to the position shown in dotted lines in Fig. 2 to permit the insertion of the lower end of the 90 hook through the slot 23. The portion 27 is then bent backward to normal position and the proportions of the lower end of the hook are such that it cannot thereafter be displaced from the bracket, so long as the 95 part 27 remains in its normal position.

A spot or lug 28 may be formed at the extreme inner end of the part 24, co-operating with a similar spot or lug 29 on the bottom portion 17 to hold a spring 30 in position to press the hook 25 outward against the attaching portion 18.

It will be noted that the parts 16 are joined to the body by curved corner portions 31 which form wings or guides in the finished brackets along both sides of the friction pad 32 which is yieldingly pressed against the head of the spool 10 by a spring 33. These wings or guides 31 prevent lateral displacement of the friction pad 110

and permit the spring 33 to be secured to the tube 11 by a single fastening only.

In Fig. 6 I have shown a slight modification in which the spool supporting member 35 is formed as a separate element welded or otherwise secured to the body of the bracket and having a portion 36 extending within the tube 11 and closely fitting against the top plate thereof. Also in this modification I have shown the bracket secured in the tube by screws 37 through the top and bottom of the tube. With this construction it is possible to omit the side portions 16 if so desired.

15. From this foregoing description, it will be seen that I have provided a spool bearing bracket which may be very easily and cheaply constructed of sheet metal and in which all parts are of adequate strength 20 and are not easily damaged or displaced. In particular, the rigid hook 25 and coil spring 30 are much more dependable than the flat spring hook heretofore used.

Having thus described my invention, I 25 do not wish to be limited to the details herein disclosed otherwise than as set forth in the claims, but what I claim is:—

1. In a tube frame, a hollow tube, a spool bearing bracket formed of a single piece of 30 sheet metal and having integral side and bottom supporting portions adapted to project within said tube, and means to secure said bracket in position.

2. In a tube frame, a hollow tube, a spool bearing bracket formed of a single piece of 35 sheet metal, said bracket having a bearing portion and having side and bottom supporting portions extending within said tube by which said bracket may be secured in operative 40 position in the tube, and means to secure said parts together.

3. In a loom, a pattern chain, a supporting tube, a spool bearing bracket comprising a chain engaging portion, a bearing portion, 45 and side and bottom portions by which said bracket may be secured in operative position in the tube, and means to secure said bracket in position, all parts of said bracket being formed of a single piece of sheet metal.

50. 4. In a loom, a supporting tube, a spool,

a sheet metal bearing bracket for said spool mounted on said tube, an elongated flat friction spring also mounted on said tube and yieldingly engaging the periphery of the spool head, and integral projections on said bearing bracket disposed at each side of the free end of said spring and preventing lateral displacement thereof.

5. In a loom, a pattern chain, a supporting tube, a spool bearing bracket secured thereto and having a relatively narrow slot therein, a chain engaging hook having an offset portion extending through said slot and within said tube, and a spring to press said offset portion yieldingly against the 65 upper inner wall of the tube.

6. In a loom, a pattern chain, a supporting tube, a spool bearing bracket having a relatively narrow slot therein, a chain engaging hook having an offset portion extending through said slot and within said tube, and a spring to press said offset portion yieldingly against the upper inner wall 70 of the tube, said bracket having a portion below said slot adapted to be bent outward 75 to permit insertion of said hook.

7. In a loom, a pattern chain, a supporting tube, a spool bearing bracket secured thereto, a substantially rigid chain engaging hook pivotally connected to said bracket and having a portion extending within said tube, and a spring in said tube for said hook.

8. In a loom, a pattern chain, a supporting tube, a spool bearing bracket secured thereto, a substantially rigid chain engaging hook pivotally connected to said bracket and having a portion extending within said tube, and a coil spring transversely disposed in said tube and engaging the inner end of said hook.

9. In a loom, a pattern chain, a supporting tube, a spool bearing bracket secured thereto, a substantially rigid chain-engaging hook pivotally mounted on said bracket and extending within the tube, and means to 95 force said hook yieldingly outward.

In testimony whereof I have hereunto affixed my signature.

EPPA H. RYON.
